CLAIM

The ornamental design for a “clip for electronic component tray”, as shown and described.

DESCRIPTION

FIG. 1 is a perspective view of the clip for electronic component tray showing our new design;

FIG. 2 is a front elevational view of the clip for electronic component tray;

FIG. 3 is a right side elevational view of the clip for electronic component tray, the opposite view being symmetrical;

FIG. 4 is a top plan view of the clip for electronic component tray;

FIG. 5 is a bottom plan view of the clip for electronic component tray; and,

FIG. 6 is a rear elevational view of the clip for electronic component tray.
